UNITED STATES PATENT OFFICE

WIEBE S. HOFSTRA, OF CLAREMONT, NEW HAMPSHIRE, ASSIGNOR TO SULLIVAN MACHINERY COMPANY, A CORPORATION OF MASSACHUSETTS

HOISTING MECHANISM

Application filed May 31, 1924. Serial No. 716,869.

This invention relates to hoisting mechanisms.

It has for its object to provide an improved hoisting mechanism. In hoisting mechanisms 5 of the portable type herein shown, it is highly desirable to provide suitable means for removably supporting the stationary casing of the drum driving motor in such a manner that the space occupied by the whole mechanism will be exceedingly small. To accomplish this function it has been found highly desirable to provide suitable means for clamping the periphery of the motor casing and to journal suitably the drums on said casing. It is one of the objects of my invention 10 to provide suitable means for clamping the periphery of the motor casing in such a manner that the space occupied by the whole mechanism will be exceedingly small. Another 15 object is to provide improved supporting means for the motor casing such as will surround and clamp the same.

In the accompanying drawings I have shown for purposes of illustration one form 20 which my invention may assume in practice.

In these drawings,—

Fig. 1 is a side elevation.

Fig. 2 is a detailed fragmentary view of a 25 part of the clamp.

Fig. 3 is a detailed view in side elevation, the drums and clamp being shown in section.

In the illustrative embodiment of my invention I have shown a double drum hoist, although it will be obvious that my improvement 30 is applicable to a single drum hoist wherein the end of the motor may be freely accessible. More specifically, the hoist comprises a base 1 having at the ends thereof standards 2 and 3. A central standard 4 is 35 carried by the base intermediate the adjacent ends of drums 5. The latter are journaled respectively in the standards 2 and 3 at their remote ends, their adjacent ends being journaled upon the motor casing 6 carried by the central standard 4.

The details of the drums and driving connections between the motor and the drums will not be fully described in view of the fact that they are of a well-known type. It will suffice to say that the driving 40 connections for the drums are controlled

through frictionally controlled members 7 and 8; and when it is desired to drive the drums, the members 7 and 8 are held stationary by friction means such as a brake, whereas when it is not desired to drive the drums 55 the members 7 and 8 are released from the friction means and allowed to rotate.

The particular way of supporting the motor casing which I have shown as illustrating my invention consists in making the central 60 standard 4 in the nature of a clamp split as at 8, lugs 9 and 10 being formed on the clamp adjacent the split and being adapted to be drawn together as by a bolt 11. When the bolt 11 is loosened, the motor casing may be 65 inserted in the clamp, after which the casing may be clamped in position by tightening the bolt 11. It is to be noted that the split of the clamp is to one side of the vertical center line to enable a suitable eye bolt 12 to 70 be disposed on the upper portion thereof for use in raising or lowering the hoist to its operating position.

In the assembling of the device the motor 75 will be inserted and clamped within the central standard, after which the end standards 2 and 3 and the drums 5, 5 will be placed upon the base, it being understood that each end standard and its respective drum is a unit 80 adapted to be assembled with the motor casing and base without necessitating removal of the motor casing or disturbing the clamping standard which in the preferred embodiment herein disclosed is made integral with the base 1. It will of course be understood that 85 the motor embodied herein may be of the electric type having a central drive shaft or of the air type wherein a plurality of intermeshing rotors may be used.

While I have in this application specifically 90 described one form which my invention may assume in practice, it will be understood that this form of the same is shown for purposes of illustration and that the invention may be modified and embodied in various 95 other forms without departing from its spirit or the scope of the appended claims.

What I claim as new and desire to secure by Letters Patent is:

1. In a hoist, a plurality of supporting 100

members comprising a standard so formed as to provide a journal and a standard so formed as to provide separable branches constituting a split clamp, a base carrying said plurality of supporting members, a motor casing held within said clamp, and a drum rotatably supported on said casing and said journal.

5 2. In a hoisting mechanism, a base, a standard positioned thereon comprising a split annular clamp, a motor casing held within said clamp, drums having their inner ends rotatably supported on said casing one at each side of said clamp, and standards carried by said base and rotatably supporting the remote ends of said drums.

10 3. In a hoisting mechanism, a base, a standard carried by said base and formed at its upper portion as two separable curved branches, connecting means therefor, one of 20 said branches extending beyond the vertical axial plane of the standard so as to form a split clamp with the connection off-set from said vertical axial plane, means on the clamp at said axial line suitable for attachment of 25 transporting mechanism, and a motor casing removably held within said branches and clamped thereby to said base.

4. In a hoisting mechanism, the combination with a driving motor having a casing 30 and a winding drum having one end surrounding and journaled on said motor casing, of a base, a standard carried by said base and formed at its upper portion as two separable curved branches, one extending beyond the vertical axial plane of the standard, so as to form a split clamp with the separation between its parts offset from said vertical axial plane, the casing of the motor being removably held within said branches and 40 clamped thereby to said base, and a second standard carried by said base and rotatably supporting the other end of the drum.

In testimony whereof I affix my signature.
WIEBE S. HOFSTRA.
